UNITED STATES PATENT OFFICE.

DIMMITT R. LOVEJOY, OF NIAGARA FALLS, NEW YORK, ASSIGNOR, BY MESNE ASSIGNMENTS,
TO WALTER E. F. BRADLEY, TRUSTEE, OF NEW YORK, N. Y.

PROCESS OF CHEMICALLY COMBINING GASES.

No. 904,072.

Specification of Letters Patent. Patented Nov. 17, 1908.

Application filed February 18, 1908. Serial No. 143,976.

To all whom it may concern:

Be it known that I, DIMMITT R. LOVEJOY, a citizen of the United States, residing at Niagara Falls, in the county of Niagara and 5 State of New York, have invented certain new and useful Improvements in Processes of Chemically Combining Gases, of which the following is a specification.

This invention relates to improvements in 10 process for effecting the union or chemical action of gases by the agency of electric arcs within or in connection with a chamber in which are contained the mixed gases to be chemically combined. In U. S. Letters 15 Patent No. 709,867, issued to C. S. Bradley and D. R. Lovejoy, September 30, 1902, and in my Patent No. 829877, dated August 28th, 1906, is described apparatus for this purpose in which cases a series of electrodes is 20 moved past another series of electrodes oppositely charged to a high tension so as to successively form, elongate, and break arcs between such electrodes, within a chamber in which the mixed gases to be united are 25 confined.

It will be apparent that in cases where chemical compounds are formed by the action of electric arcs on gases, as for instance in the formation of oxids of nitrogen, that 30 the heat of the arcs operates in two ways to reduce and limit the amount of chemical combination and even break up such compounds when formed. In the first place since the temperature of the gaseous mixture is as a whole considerably increased by 35 the heat of the arcs, the vapor tension of the compounds formed is increased in a like proportion and inasmuch as it is probable that the amount of such compounds formed 40 bears a definite relation to the tension of its vapor as related to the tensions of the unconverted gases, it will be evident that if the compound or compounds formed are readily condensable or liquefiable at low temperature 45 as compared with the unconverted gases (which is equivalent to saying that their vapor tensions are more rapidly reduced with reduction of temperature), that such compounds will be more abundantly formed 50 at lower temperatures than at high temperatures and that if the temperature of the whole gaseous mixture be reduced to the point of liquefaction or still better of solidification of the compounds formed that such 55 compounds will be more rapidly, easily, and

abundantly formed than at higher temperatures. In the second place if the temperature of the whole mass of gases were allowed to rise, due to the heat of the arcs, a point would be reached at which the compounds 60 would suffer dissociation after having been formed and with consequent loss of efficiency. Therefore taking these two causes into consideration it is clear that if the temperature be allowed to rise, the efficiency of production is materially interfered with and that on the contrary if the temperature be reduced the operations will be conducted to much greater advantage. In order to obviate this injurious effect of heat, my present improvement consists in subjecting the 65 gases to artificial refrigeration either preliminary to or simultaneously with the action of the electric arcs.

In the accompanying drawings I have 70 shown, diagrammatically, two forms of apparatus by which my process may be carried into effect in the different ways above indicated.

Figure 1 is a diagrammatic longitudinal 75 section of an apparatus adapted for subjecting the mixed gases to refrigeration, immediately before their admission to the chamber where they are subjected to the effect of electric arcs, as described in my prior patent 80 No. 829,877, hereinbefore referred to. Fig. 2 is a similar view in which the gases are subjected to the refrigerating action within the chamber through which they are passed 85 under the influence of the electric arcs, and simultaneously to their subjection to the 90 effect of such electric arcs.

Referring to Fig. 1, 1 represents a cylinder having numerous fixed electrodes 2 projecting from its inner periphery. 3 represents 95 a shaft mounted centrally and rotating within the cylinder 1 and carrying a number of movable electrodes 4 connected mechanically and electrically with the said shaft. 5 represents the induction pipe for 100 admission of fresh mixed gases, (atmospheric air, for example), and 6, 6 outlet ducts for the removal of the nitrogen compounds formed under the treatment. 7 indicates an 105 exhaust fan to illustrate suitable means for causing the flow of gases through the chamber; 8 a suitable source of high tension electric currents, either unidirectional or alternating, and 9 a series of inductances or 110 choke-coils each having one terminal con-

neected individually to the fixed electrodes 2 and, in practice, having their other terminals grouped together and connected to one pole of the generator 8, the circuit being completed by connecting the shaft 3, by means of a conductor with the other pole of the generator 8. The shaft 3 is preferably mounted in insulating bearings 10 and 11 at top and bottom as described in my prior application, 10 and the stationary electrodes 2 mounted in tubes or bushings 14 of porcelain or other insulating material set in packings in the cylinder adapted to prevent the passage of gas and also to permit the radial adjustment 15 of the fixed electrodes 2 relatively to the electrodes 4 which revolve in proximity to such stationary electrodes. 61 represents a chamber in the induction pipe 5 containing a coil 62 through which ammonia or refrigerated brine or other refrigerating agent is caused to flow by customary means so that by contact with such coil the inflowing gas 20 will be subjected to refrigerating action immediately before entering the cylinder 1.

25 In Fig. 2 similar reference characters indicate corresponding parts. 61^a represents a jacket surrounding the cylinder 1 and 62^b a refrigerating coil therein through which coil a refrigerating agent is caused to flow as before described, so as to cool the entire cylinder and the body of mixed gas therein during action of the electric arcs on said gases.

In another application of even date here-with I have described a method of subjecting 35 gases to radiant energy from a suitable source of such energy, in conjunction with electric discharges to effect or facilitate chemical union of such gases. My present improvement also relates to the subjecting 40 of gases to refrigerating action in conjunction with the combined action of electric discharges and independent radiant energy from any suitable source of such energy.

The temperature of the air is preferably 45 reduced to about that of solidification of nitric fumes; say—150 C. so that the nitric fumes as soon as formed will liquefy; or the temperature may be reduced only to that at which nitric fumes liquefy say—30 C. It

is evident also that, while this invention has 50 been described with particular reference to the formation of oxids of nitrogen by means of electric discharges in the form of arcs, it is also applicable to the formation of other compounds and also in combination 55 with electrical discharges in the form of sparks or silent discharges.

The broad idea of this invention is the reduction of the tension or pressure of compounds formed in order to facilitate such 60 formations by electrical discharges of any kind.

Having thus described my invention, the following is what I claim as new therein and desire to secure by Letters Patent:—

1. The process of effecting or promoting chemical reaction in gases, which consists in subjecting the gases to the action of electric arcs and removing the products formed from the region of the arcs by refrigerating the 70 same to reduce said products to a nongaseous state.

2. The process of effecting or promoting chemical reaction in gases, which consists in subjecting the gases to the action of electric 75 arcs, successively and repeatedly striking, elongating and breaking said arcs and removing the products formed from the action of said arcs by refrigerating the same to a nongaseous state.

3. The process of effecting or promoting the chemical combination of nitrogen and oxygen, which consists in subjecting said gases to the action of the electric arc and simultaneously refrigerating the nitrous 85 oxids formed to reduce the same to a liquid or solid condition.

4. The process of effecting or promoting the chemical combination of gases, which consists in subjecting said gases to the action 90 of electric arcs of minimum volume and simultaneously subjecting the gases to refrigeration to reduce the compound formed to a liquid or solid condition.

D. R. LOVEJOY.
